(57) **CLAIM**

The ornamental design for a tongue cleanser, as shown and described.

DESCRIPTION

FIG. 1 is a front elevation view of a tongue cleanser, showing an embodiment of my new design, the rear elevation view being identical thereto;

FIG. 2 is a top plan view thereof, the bottom plan view being identical thereto;

FIG. 3 is a left side elevation view thereof;

FIG. 4 is a right side elevation view thereof.

FIG. 5 is a front elevation view of an alternate embodiment of the tongue cleanser, the rear elevation view being identical thereto;

FIG. 6 is a top plan view thereof, the bottom plan view being identical thereto;

FIG. 7 is a left side elevation view thereof; and

FIG. 8 is a right side elevation view thereof.

FIG. 9 is a front elevation view of another alternate embodiment of the tongue cleanser, the rear elevation view being identical thereto;

FIG. 10 is a top plan view thereof, the bottom plan view being identical thereto;

FIG. 11 is a left side elevation view thereof;

FIG. 12 is a right side elevation view thereof; and,

FIG. 13 is a perspective view thereof, showing the top, right side, and rear.

The broken lines shown in FIGS. 1, 2, 4, 5, 6, 8, 9, 10, 12 and 14 illustrate portions of the tongue cleanser that form no part of the claimed design.
